METHOD AND DEVICE FOR EFFECTING
FUMIGATIONGeorge L. Hockenyos, Springfield, Ill., assignor to
Monsanto Chemical Company, St. Louis, Mo.,
a corporation of Delaware

Application April 12, 1935, Serial No. 15,945

2 Claims. (Cl. 21—58)

The present invention relates to fumigants for exterminating such insect and rodent pests as infest dwellings, storage rooms, ships and similar structures, and it has particular relation to materials for the generation of sulfur dioxide for use in such capacity.

The main objects of the invention are to provide:

Materials for generating sulfur dioxide for fumigation purposes in which the formation of the deposit of solid sublimed sulfur upon the surfaces of articles to be fumigated is obviated;

A package for the storage and shipment of highly inflammable materials capable upon combustion of generating sulfur dioxide, which will not permit spilling of the inflammable materials upon rupture of the container;

A package for storage and shipment of highly inflammable materials capable of generating sulfur dioxide upon combustion which may be employed as a highly efficient burner for generating the sulfur dioxide fumes during processes of fumigation.

These and other objects will be apparent from perusal of the following description and consideration of the accompanying drawing.

In the drawing Figure I is an elevational view of a package embodying the principles of the invention in actual operation. Figure II is a plan view of the embodiment of the invention disclosed in Figure I disclosing the manner of opening the package.

The use of sulfur dioxide as generated by the burning of elemental sulfur for purposes of destroying insect and rodent pests in ships, buildings and similar structures has long been common practice. However, such process has never proven to be completely satisfactory for application to dwellings and other structures which contain relatively delicate furnishings. This is true because the sulfur during the step of burning tends to sublime or otherwise give off fumes containing elemental sulfur. These fumes form whitish deposits upon the surfaces of the articles to be treated which, in the case of painted and lacquered surfaces, are highly objectionable. Because of this defect the use of sulfur as a fumigant has of late years been in many cases supplanted by cyanide gases which are highly effective as destroyers of insect and rodent pests but which are extremely poisonous to higher forms of life and are also difficult to detect even in concentrations which may be deadly to man. Because of these defects of cyanides extreme precautions must be observed in using them.

In my copending application, Ser. No. 758,236, filed December 19, 1934, is disclosed a process of generating sulfur dioxide by the combustion of carbon bisulfide. In this process the objectionable deposition of elemental sulfur films upon painted, lacquered or other delicate surfaces is entirely obviated. In the above prior application, in order to obviate the possibilities of excessively rapid combustion or of explosions, the carbon bisulfide is absorbed in a suitable material such as kieselguhr, diatomaceous earth, cotton waste, etc. which permits the inflammable vapors to escape gradually and obviates violent combustion.

The present invention involves the provision of a package for the materials disclosed in my copending application which is highly efficient in retaining the carbon bisulfide during storage or shipment, which package also is susceptible of acting as a highly efficient burner for the carbon bisulfide material.

Broadly stated, the invention comprises the provision of a package of carbon bisulfide absorbed in a suitable material and hermetically sealed in a metallic container of such character that it may be readily opened at the top and provided with punctures adjacent to the bottom which permit the carbon bisulfide to ignite and the flames to play upwardly along the side of the container in order to heat the contents and thus completely to expel the carbon bisulfide in vapor phase.

In the form of the invention disclosed the carbon bisulfide is admixed with any convenient absorbent. Kieselguhr is found to be quite satisfactory for this purpose. Approximately three-fourths of a pound of kieselguhr will contain approximately three pounds of carbon bisulfide without any tendency of the liquid to flow therefrom upon opening of the container in which the material is packed. This mixture of carbon bisulfide and kieselguhr is incorporated into an ordinary tin can 4 of the type of a tomato can of convenient size, and having a bottom 5 soldered thereupon. A can of approximately one quart capacity is found to be quite convenient for most purposes though, of course, larger or smaller cans may be employed if desired. It is to be understood that the can is to be formed of sheet metal (e. g. mild steel) of adequate thickness and rigidity to prevent accidental rupture of the can during ordinary usage. However, it should be sufficiently thin to admit of opening and slitting the sides of the package by means of an ordinary knife or other convenient instrumentality. It

is found that when carbon bisulfide is stored in kieselguhr or other suitable absorbents in accordance with the provisions of this invention, the cans containing it may readily be sealed in ordinary manner merely by securing a cover 6 by a conventional crimp seal 7.

Packages of fumigant as thus prepared are hermetically sealed and, of course, may be stored for an indefinite period of time without any loss due 10 to evaporation of the contents or without any fire hazard. The cans will withstand internal pressures generated even when the cans are heated up to 150° F., and even if they are heated up to the point of rupture, there is no serious explosion. 15 If in handling the packages the tin containers should accidentally be ruptured, which occurrence is improbable, there is but little fire hazard involved because the absorbent retains the liquid and prevents it from spilling. The escape of the 20 carbon bisulfide as a vapor from the ruptured container is so slow that in any reasonably well ventilated place of storage the concentration of vapors cannot become sufficiently high to be dangerous.

25 When it is desired to employ the material for generating sulfur dioxide, as well as the attendant CO₂ which also results from the burning of CS₂, for fumigation purposes the container, may be opened at the top, for example by forming 30 cross slits 8 in the top 6. It is not necessary to pry the flaps or tabs 9 thus formed upwardly but instead they may be left in position allowing the carbon bisulfide vapors merely to escape through the slits. By this method excessively rapid combustion of the carbon bisulfide over a relatively 35 large zone at the top of the can upon opening the latter is obviated.

Adjacent to the bottom of the can a plurality of openings are pierced and they may take the 40 form of vertical slits 11 as shown in the drawing. Slits of this character are found in actual practice to be preferable to round openings or to transverse slits because they permit the carbon bisulfide vapors to flow upwardly along the vertical 45 surfaces of the container rather than being projected horizontally to a distance from the latter. By thus flowing along the surfaces the vapors, upon ignition, more effectively warm the contents of the cans than is possible where they 50 are projected horizontally. The container may, of course, be provided with a suitable paper wrapper having trade-marks, instructions and such similar matter printed thereupon. It is also desirable to print upon the label marks indicating 55 the position in which the vertical slits are to be formed. These marks may also be identified by such labels 17 as "Slit here" or other similar instructions. It will also be appreciated that instead of providing the containers with separate 60 paper wrappers they may be lithographed in con-

ventional manner. If desired, the points for the formation of the vertical slits may further be marked by small indentations in the walls of the container.

It will be appreciated that in the operation of 5 this form of the invention the burning of carbon bisulfide vapors emitted through the openings cut in the sides of the cans insures that the contents of the bottom of the can will be rapidly and completely vaporized thereby insuring that the material will be burned within the shortest possible period of time commensurate with safety. This is highly desirable because if the material burns over an unduly long period of time there is considerable accidental loss of the sulfur dioxide from 10 the space to be fumigated before the combustion is complete. Therefore, the sulfur dioxide never attains the maximum possible concentration and the fumigating action is never as intense as it is where the concentration of sulfur dioxide is 15 brought immediately to its highest value.

It will thus be apparent that I have provided a relatively inexpensive package for the preservation and use of carbon bisulfide as a fumigant which may be handled and stored with safety over 20 long periods of time and which acts as a highly efficient burner for carbon bisulfide during fumigation operations.

Although I have shown and described only the 25 preferred forms of the invention it will be apparent that numerous modifications may be made therein without departure from the spirit of the invention or the scope of the appended claims.

What I claim is:

1. A method of burning carbon bisulfide to form sulfur dioxide in fumigation operations which comprises puncturing the top and lower side wall portions of a sealed non-combustible vessel containing carbon bisulfide absorbed in a 40 porous material and igniting the carbon bisulfide vapors issuing from the ports formed by said puncturing while allowing the flames issuing from the lower side wall ports to play upwardly along the vessel to evaporate completely the carbon bisulfide in the upper part of the container.

2. An apparatus for the generation of a fumigating gas containing SO₂ from CS₂ absorbed in a porous refractory material contained therein and filling it, comprising a normally hermetically 50 sealed sheet metal container with slits formed in the top thereof and slits formed along the side walls adjacent the bottom thereof, said slits adjacent the bottom being adapted for ignition of CS₂ vapors in order to heat the contents of the container above said slits along the side walls, and thus to vaporize CS₂ from said porous material for combustion at the top of said container.
